DESIGN FOR A TROLLING SPOON

Joseph Scheeland Gardemeyer,
San Francisco, Calif.

Application October 19, 1946, Serial No. 134,068

Term of patent 14 years

(Cl. D31—4)

To all whom it may concern:

Be it known that I, Joseph S. Gardemeyer, a citizen of the United States, residing at 508 Scott Street, city and county of San Francisco, and State of California, have invented a new, original, and ornamental Design for a Trolling Spoon, of which the following is a specification, reference being had to the accompanying drawing, forming part thereof.

Fig. 1 is a perspective view of a trolling spoon showing my new design.

Fig. 2 is a plan view of the trolling spoon shown in Fig. 1.

Fig. 3 is a side elevation of the trolling spoon shown in Fig. 1.

The essential features of my design reside in the portion shown in full lines.

I claim:

The ornamental design for a trolling spoon, as shown and described.

JOSEPH SCHEELAND GARDEMEYER.
